UNITED STATES PATENT OFFICE.

CHARLES B. CLER, OF NEW YORK, N. Y.

NON-REFILLABLE BOTTLE.

1,148,503.

Specification of Letters Patent.

Patented Aug. 3, 1915.

Application filed October 2, 1914. Serial No. 864,569.

To all whom it may concern:

Be it known that I, CHARLES B. CLER, a citizen of the United States, residing at New York city, borough of Manhattan, in the county and State of New York, have invented a certain new and useful Improvement in Non-Refillable Bottles, of which the following is a specification.

The invention relates to that class of anti-refilling devices in which a valved closure is introduced in the neck of the bottle, and the object of the invention is to provide a closure of this character which will serve efficiently and may be economically manufactured and easily applied and secured.

The invention consists in certain novel features and details of construction and arrangement by which the above objects are attained, to be hereinafter described and claimed.

The accompanying drawings form a part of this specification and show on an enlarged scale an approved form of the invention.

Figure 1 is an axial section through a bottle-neck and the closure or plug therein. Figs. 2, 3 and 4 are transverse sections, taken on the lines 2-2, 3-3 and 4-4 respectively of the preceding figure. Fig. 5 is a side elevation of the valve. Fig. 6 is a corresponding view at a right angle to Fig. 5.

Similar letters of reference indicate the same parts in all the figures.

A is a bottle-neck which may be of the usual form externally and having its interior cylindrical or only slightly tapered, to receive a cylindrical cartridge or plug introduced after the bottle has been filled, and containing the valved passages through which the contents of the bottle may be poured out.

The plug is in two parts, B and C, the uppermost B consisting of a hollow cylindrical shell terminating at the upper end in a contracted opening b surrounded by a neck or flange B¹ through which the contained liquid is delivered from the bottle. Below the opening b and inclosed axially within the shell is an inverted cup D of less diameter than the interior of the shell to provide an annular passage b¹ between these portions, and at the lower edge of the cup rim is an exterior conical or flaring annular flange D¹ extending angularly upward and outward toward the interior of the shell, overlapped by a similar flange E² on the interior of the shell extending nearly to the

cup D. The annular passage between the flange D¹ and the shell is marked d and the annular passage between the flange B² and the cup is marked b².

The shell and its contained cup are preferably formed integrally from porcelain, glass, or other suitable material and are joined by posts or studs E extending from the flange D¹ to the flange B² and located at suitable intervals. The lower portion C of the plug may be of the same material and consists of an annulus having a circumferential rabbet or offset at C¹ on the upper margin to receive the skirt of the shell B, and a similar rabbet on the lower face at C² receives a ring or gasket F of cork or analogous material adapted to be compressed between the annulus and interior of the bottle-neck to guide and hold the plug during insertion and to close the joint between the neck and annulus against the passage of liquid.

The upper face of the annulus is plane and forms the seat for a valve G of aluminum or other material, of disk form lying thereon and having an openwork downward extension G¹ received in the axial passage in the annulus to guide the valve in its opening and closing movements. A delicate helical spring H of bronze or other non-corrosive material holds the valve lightly to its seat and abuts at one end within the inverted cup D and at the other upon the upper face of the valve G on which is a boss G² encircled by the end of the spring and serving as a guide for the latter. The spring H should be light enough to permit the valve to leave its seat under the pressure of the contained liquid when the bottle is canted or inverted, and of sufficient expansive force to return the valve to its seat when relieved from such liquid pressure.

To insert the plug the parts are first assembled with the skirt of the shell received in the rabbet C¹ of the annulus, the whole is then forced into the neck of the filled bottle against the resistance offered by the cork gasket F until the desired location is reached, a suitable cement J is then applied to fill the annular space between the flange B¹ and the neck of the bottle which on hardening holds the shell firmly in place, the annulus being held by the frictional contact of its gasket F. The mouth of the bottle may then be closed by a cork L, and capped as usual if the plug be located as shown in Fig.

1, or if the plug be forced into the neck a less distance so that the flange B^1 lies about flush with the bottle-mouth, as will be understood without illustration, the closure may be effected by simply inserting a small cork into the pouring orifice b . On tilting the bottle the contained liquid will escape by lifting the valve and flowing through the annular passages between the cup and shell, and refilling is prevented by the closing of the valve aided by its spring.

The plane upper face of the inverted cup D is of greater area than the orifice b and with the flanges D^1 B^2 serves effectually to prevent the insertion of a wire or other instrument to lift the valve for refilling.

It will be noted that the device consists of few parts, the shell, annulus, valve, spring, and gasket, easily and cheaply produced and inserted. The compressible gasket F and the cement J permit the device to accommodate itself to slight irregularities in the bottle-neck, and the latter requires no special construction other than to be formed approximately cylindrical on its interior.

Modifications may be made in the forms and proportions of the parts and in the ma-

terials employed, as may be found necessary or desirable in adapting the invention for service under various conditions.

30

I claim:

A bottle closure comprising a plug in sections, the uppermost being in the form of a hollow cylindrical shell with a contracted opening at one end, and a lower part having a circumferential offset portion receiving the inner end of the shell, a compressible gasket receiving the inner end of said lower portion and between which and said inner end of the shell said offset is disposed, a valve seated on the lower portion, said shell having oppositely disposed overlapping internal flanges and an inverted cup-shaped member integral with said flanges, there being an annular passage between the outermost flange and the cup and a spring within said cup bearing upon the valve.

In testimony that I claim the invention above set forth I affix my signature, in presence of two witnesses.

CHARLES B. CLER.
